6 Claims. (Cl. 24—248)

ABSTRACT OF THE DISCLOSURE

A two-piece fabric clasp designed especially as a diaper fastener and which is devoid of fabric-penetrating points or sharp edges. A spring wire frame establishes a fabric-receiving slot and a bell crank having a long manipulating arm and a short fabric-engaging arm forces the fabric between two opposed portions of the frame and spreads the same thereagainst. A self-locking action under the influence of compressional forces exerted on the fabric holds the bell crank in an over-center position against release.

The improved fabric fastener comprising the present invention has been designed for use primarily as a diaper clasp for holding the overlapping edge regions of a diaper or other breechcloth in position against separation or relative shifting movements when in its applied position. The invention is however capable of other uses and fabric fasteners embodying the principles of the present invention may, if desired, with or without modification as required, be employed for securing the overlapping portions of various other types of garments such as blankets or the like in their overlapping relationship. Irrespective however of the particular use to which the invention may be put, the essential features thereof are at all times preserved.

Broadly considered, fasteners for diapers may be divided into two general classes, namely diaper pins and diaper clasps, the former having associated therewith one or more fabric-penetrating shank portions and the latter being devoid of such portions and usually being provided with opposed fabric-gripping jaws similar to those employed in connection with conventional necktie clasps. Diaper pins are possessed of numerous limitations, principal among which is the hazard offered to the infant by the sharp points of the pin shanks. Although many conventional diaper pins make provision for shielding these points, the shielding is not effective until the diaper pins are closed and thus there is danger in applying them. Furthermore difficulty is encountered in forcing the pin shanks through the fabric material, this being especially true where a large number of fabric layers are involved. According to present day diaper application procedure, a minimum of six fabric layers is involved for each pin shank penetration but frequently, to reduce the size of the leg openings of the applied diapers, edge folds are resorted to which increase the number of layers to nine. Ultimately the points of the pin shanks become dull and the article is then usually discarded.

A further limitation that is attendant upon the construction and use of conventional pin type fasteners resides in the fact that when the material undergoing fastening is of a fragile nature, as for example satin binding as applied to blankets, or the closely woven cotton fastening tabs of an infant's undershirt, penetration thereof by the pin shanks weakens the fabric. Since the holes which are created by the punctures are not self-healing as is the case with loosely woven cloth, repeated application of pin type fasteners thereto results in deterioration and short fabric life. Finally the use of diaper pins having fabric-penetrating shanks require that any given penetra-

tion be made at a region well within the margins of the material so that tensional forces will not subsequently rupture the material. However, careful selection of a proper penetration point must be made lest too much material be gathered to prevent closing of the diaper pin. These and other limitations that are attendant upon the construction and use of conventional diaper pins operate in favor of the use of diaper clasps as an alternative.

Conventional diaper clasps are also possessed of certain limitations, one such limitation being lack of proper holding power. Most diaper clasps rely upon spring pressure to maintain the clasp yieldingly in its closed condition and when this spring pressure is exceeded the clasp will allow slippage of the fabric or other breech material. Where spring pressure is increased to resist such slippage, additional manual force is required to open the clasp preparatory to its application and this obviously places a limitation upon the over-all thickness of the composite material undergoing fastening. Normal finger strength also places a limitation upon the extent to which spring pressure may be increased.

In an effort to prevent either fabric-to-fabric or fabric-to-clasp slippage, some clasp type fasteners are provided with serrated clamping jaws but these have a tendency to ensnare the fabric fibers and render it difficult either to install or remove the clasps. Where the clasps are employed on materials other than diapers which are fragile, puncturing of the material by the serrations sometimes results. In the case of rubberized fabrics, there is a tendency for the jaw serrations to become clogged due to shredding of the elastomeric material.

The present invention is designed to overcome the above-noted limitations that are attendant upon the construction and use of both pin type and clasp type diaper and other similar fastening devices and, toward this end, the invention contemplates the provision of a novel two-piece, articulated, clasp type fastener which, although it operates upon the opposed jaw principle, is so constructed that one of the jaws associated therewith is capable of moving to an over-center position under the yielding pressure offered by the fabric or other material undergoing clamping, thereby locking the fastening device against dislodgment under the influence of any spreading action which the material is capable of exerting upon the jaws. This feature of the invention constitutes one of the principal objects thereof.

In carrying out the above-mentioned object, the invention contemplates the provision of a diaper clasp having a framework presenting a fixed bifurcated anvil jaw, and a lever which is fulcrumed on an axis above the level of the anvil jaw, one arm of the lever constituting a cooperating jaw. The lever is freely movable between a raised position wherein the lever arm or jaw is remote from the anvil jaw so that the overlapping portions of the fabric or other diaper material may be introduced edgewise between the two jaws, and a lowered position wherein the lever jaw enters between the bifurcations of the anvil jaw, thus forcing the intervening regions of the fabric material between the bifurcations, a stop for the movable lever jaw being provided after the latter has swung beyond its dead center position. By such an arrangement, not only are the overlapping layers of the fabric material forced hard against each other, but additionally the clamping area which is exerted thereon is increased due to the arcuate bias which is applied thereto so that resistance to fabric-to-fabric slippage is greatly enhanced. Additionally, because the overlapping layers of the fabric material are introduced edgewise between the jaws, the direction of such tensional forces as ordinarily are prevalent with folded and applied diapers is at a right angle to the direction of swinging movement of the movable

lever so that these forces do not oppose the direction of closing movement of the movable lever and there is no tendency for them to overcome the previously mentioned over-center locking action.

An additional feature of the present invention resides in the provision of dual or two-way locking action which obtains when the movable lever assumes its final position against the aforementioned stop provided for it at the time it moves to its over-center fully closed position. Not only does this locking action lock the lever against both over-travel and regression, but it also locks the bifurcations of the anvil jaw against the spreading action which otherwise would be applied thereto under the influence of any pulling action thereon which may be exerted by tension in the diaper fabric or other breech material.

Yet another and important feature of the present invention resides in the maintenance of a predetermined friction differential between the fabric and the anvil jaw on one hand and the fabric and movable lever jaw on the other hand. Whereas, with equal friction in both cases extreme difficulty might be encountered in moving the movable jaw to its closed condition of cooperation with the fixed anvil jaw, a lessening of the frictional characteristics exerted by the movable lever upon the fabric will allow the lever to slide or slip upon the fabric at the time the lever is moved toward its closed position, while at the same time the fabric is held against sliding on the anvil jaw so that there will be no tendency for the fabric to adhere to the moving jaw and thus slide on the fixed anvil jaw to a position wherein it will not become securely clamped between the two jaws.

The provision of a diaper clasp which is extremely simple in its construction and which therefore may be manufactured at a low cost; one which is comprised of but two relatively movable parts and which therefore is unlikely to get out of order; one which is rugged and durable and which therefore will withstand rough usage; one which is capable of ease of manipulation under all conditions of usage; one which readily lends itself to card mounting for display purposes without requiring extraneous tie wires, staples or other fastening devices; one which is attractive in its appearance and pleasing in its design; and one which, otherwise, is well adapted to perform the services required of it, are further desirable features which have been borne in mind in the production and development of the present invention.

Other objects and advantages of the invention, not at this time enumerated, will readily suggest themselves as the nature of the invention is better understood.

In the accompanying single sheet of drawings forming a part of this specification, one illustrative embodiment of the invention has been shown.

In these drawings:

FIG. 1 is a rear perspective view of a diaper fastener constructed according to the present invention and showing the same in an open condition;

FIG. 2 is a perspective view similar to FIG. 1 showing the fastener in its closed condition;

FIG. 3 is a side elevational view of the fastener;

FIG. 4 is a sectional view taken substantially on the line 4—4 of FIG. 3;

FIG. 5 is an enlarged sectional view taken on the line 5—5 of FIG. 3;

FIG. 6 is a sectional view taken substantially on the line 6—6 of FIG. 3 showing the fastener in its open condition preparatory to becoming closed upon the overlapping portions of a fabric; and

FIG. 7 is a sectional view similar to FIG. 6 but showing the fastener closed upon the fabric.

Referring now to the drawings in detail and in particular to FIGS. 1 to 5 inclusive, a diaper fastening device has been designated in its entirety at 10 and it involves in its general organization two hingedly connected parts, namely a base framework 12 which is generally U-shape in vertical longitudinal cross section and a lever 14 in

the form of a bell crank. As will be described in greater detail presently, the framework 12 is comprised of a single length 16 of spring wire stock, preferably stainless steel, bent to a predetermined configuration and having a limited portion of its length coated or covered with a jacket 18 of an elastomeric material.

As best seen in FIGS. 1 to 3 inclusive, the framework 10 includes a base structure or support 20 (designated by brackets in the various views), and a super structure 22 (similarly designated by brackets). The base structure 20 is generally U-shape in horizontal longitudinal cross section and includes a pair of substantially parallel arms 24 and an interconnecting bight portion 26, the latter being raised slightly above the generally horizontal plane of the arms 24 as clearly shown in FIG. 3. The parallel arms 24, in effect, define an elongated slot 25 therebetween. The superstructure 22 similarly includes a pair of substantially parallel arms 28 and an interrupted or split bight portion 30 (FIGS. 6 and 7). The arms 28 are inclined with respect to the arms 24 at an angle of approximately 30° and are joined to the latter arms by reverse reentrant bends 32. The arms 28 are somewhat shorter than the arms 24 so that the interrupted bight portion 30 overlies the general plane of the arms 24 and extends transversely of the superstructure along a horizontal axis which is displaced forwardly from the central vertical transverse plane of the framework.

The elastomeric jacket 18 is substantially coextensive with the two arms 24 of the base structure 20 and the interconnecting bight portion 26, the jacket being of tubular construction and the ends thereof terminating in the vicinity of the reentrant bends 32. Preferably the jacket is formed of a suitable elastomeric material such as rubber, either natural or synthetic or a rubber substitute. Under certain circumstances, the jacket may be formed of a suitable plastic material having good frictional characteristics for purposes that will be made clear presently. The manner in which the jacket is applied to the wire stock 16 forms no part of the present invention, various means such as vulcanization, dipping, spraying or other suitable processes being contemplated. If desired the tubular jacket may be preformed and subsequently telescopically applied to the wire stock, either before or after the latter has been bent to form. Preferably however the jacket 18 is applied to the wire material by a dipping operation to assure good adhesion and to prevent looseness. Such a dipping operation also facilitates application of the jacket inasmuch as application of a preformed jacket to a sharp angular bend would otherwise involve installation difficulties. Alternatively, the jacket may be applied by a molding operation, followed by a vulcanization process. If desired, the jacket may be formed of a suitable plastic material which is molded in position and subsequently polymerized. Irrespective however of the particular material involved or the manner of applying the jacket, the essential features of the invention remain the same.

The lever 14, as previously stated, is in the form of a solid body which preferably is of a molded plastic material such as Teflon or a suitable phenol condensation product which, when polymerized, exhibits a low coefficient of friction for reasons that will be set forth subsequently. The lever, being in the form of a bell crank, includes a generally bulbous body portion 40 (FIG. 3) which constitutes one arm of the bell crank, and a generally flat manipulative actuating or handle portion 42 of slightly greater width than the body portion 40 so as to provide, in effect, a pair of side wings 44 the function of which will become apparent presently. A transverse bore 46 is provided adjacent the proximate end of the body portion 40 and receives therein the two turned ends of the wire stock 16 which constitute the interrupted or split bight portion 30 so that these ends constitute, in effect, trunnion supports at the outer or distal end of the superstructure 14 for the lever or bell crank 14 as a

whole. It is to be noted that the generally flat handle portion 42 merges gradually with the bulbous body portion 40 as best seen in FIG. 3 so that one effective arm of the bell crank is afforded in its entirety by the body portion 40 while the other effective arm of the bell crank is afforded partly by the body portion 40 and partly by the flat handle portion 42.

The bell crank 14 is thus freely fulcrumed on the framework 12 for swinging movement between the raised retracted position wherein it is shown in FIG. 1 and in dotted lines in FIG. 3 and the lowered advanced position wherein it is shown in FIG. 2 and in full lines in FIG. 3. In the raised position of the bell crank 14, the diverging base structure 20 and superstructure 22 establish, in effect, a forwardly opening unobstructed mouth for edgewise reception of the overlapping edge portions of the diaper fabric. In the lowered position of the bell crank, the bulbous body portion 40 thereof descends in the manner of an eccentric cam upon the fabric and forces the latter downwardly as shown in FIG. 7 between the parallel arms 24 of the base structure and into the slot 25 defined thereby, the lower or distal tip of the body portion 40 projecting completely through the slot 25 as clearly shown in FIGS. 2 and 3. The swinging movement of the bell crank 14 is limited by the provision of the two side wings 44 which come to rest upon the medial regions of the respective inclined arms 28 of the superstructure 22, these arms seating within grooves 50 (FIG. 4) which are defined by the juncture between the side wings and the central part of the handle portion 42. As will be explained in greater detail presently the seating of the handle portion 42 on the arms 28 and the partial confinement of the later within the grooves not only limits the extent of swinging movement of the bell crank 14, but it also confines the arms 28 in their parallelism and prevents outward spreading of these arms under the wedging action of the bulbous body portion 40 of the bell crank 14 which enters between the arms 24 and exerts a wedging action thereon which is transmitted to the arms 28 through the reentrant bends 18, all in a manner that will become apparent when the operation of the present diaper clasp is set forth. To facilitate raising of the bell crank from its lowered position to release the overlapping portions of the diaper fabric, the outer or distal edge region of the handle portion 42 is undercut as indicated at 52 in FIG. 3, thereby affording a reaction surface for the fingernail of the user when releasing the clasp.

In the operation of the herein described diaper clasp 10, the overlapping edge portions of the folded diaper fabric are introduced edgewise and rearwardly through the open mouth of the framework 12 as heretofore described until the extreme edges thereof become seated within the crotch which is defined by the reentrant bends 32 (FIG. 3). This is accomplished by the simple expedient of hooking the framework, so to speak, over the overlapping edges of the fabric. The clasp then assumes the relationship with respect to the fabric which has been illustrated in FIG. 6, the overlapping regions of the fabric being designated at F in this view. Thereafter, by manually engaging the handle portion 42 of the bell crank 14, the latter is swung in a counterclockwise direction as seen in FIG. 3, thus causing the bulbous body portion 40 of the bell crank to descend upon the fabric F and depress or force the same downwardly as shown in FIG. 7 so that it enters between the parallel arms 24 and becomes firmly clamped between these arms and the bulbous body portion 40. Although this forcible entry of the fabric between the arms 24 may cause a limited amount of spreading of the arms due to the spring characteristics of the wire material 16, undue spreading thereof is prevented by the aforementioned locking action exerted by the interlock between the arms 28 and the grooves 50 which are formed in the handle portion 42 of the bell crank.

It is to be noted at this point that during the downward swinging movement of the bulbous body portion 40 of the bell crank, the low frictional characteristics which are offered by the smooth plastic material of the bell crank 5 allow the distal end of the body portion 40 to slide upon the fabric and move to the over-center position illustrated in FIG. 3 where the upward force of the compressed fabric serves to yieldingly urge the bell crank in a locking direction and thus lock the bell crank in this position. At the same time, the relatively high frictional characteristics offered by the elastomeric material of the jacket 18 which covers the arms 24 prevent sliding of the fabric upon these arms and thus eliminates the danger of the fabric slipping from the anvil jaw which is established by these arms. The upturned bight portion 26 also assists in restraining the fabric from slipping from the anvil jaw and it further serves as a contour relief portion for the applied clasp so that the distal end of the anvil jaw will not project against the body of the infant and cause discomfort, it being noted that this portion of the clasp 10 ordinarily comes into contact with the body at the juncture region between the torso and the hips. It is to be further noted that the bight portion 26 is disposed an appreciable distance forwardly of the body portion 40 of the bell crank when the latter is in its locking position and thus the binding action on the fabric layers is substantially entirely against the parallel arms 24 of the base structure with practically no binding action existing between the bight portion 26 and the body portion 40 of the bell crank. By such an arrangement, the bight portion 26 offers no resistance to movement of the bell crank to its fully locked position.

Release of the clasp is effected by raising the handle portion from its seated position on the parallel arms 28, 35 this being accomplished by initially inserting the fingernail beneath the relieved or undercut portion 52 (FIG. 3). The bell crank 14 is thus swung in a counterclockwise direction and, again, the difference in frictional characteristics between the plastic material of the bell crank and 40 the elastomeric material of the wire covering or jacket 18 holds the fabric from bunching in the crotch region afforded by the reentrant bends 32 and allows the body portion 40 of the bell crank to slide upon the fabric to its position of release. After such release, the clasp 10 may 45 be bodily slipped or unhooked, so to speak, from the overlapping edge portions of the folded diaper fabric.

The invention is not to be limited to the exact arrangement of parts shown in the accompanying drawings or described in this specification as various changes in the 50 details of construction may be resorted to without departing from the spirit of the invention. For example, although the framework 12 of the clasp has been shown and described herein as being formed, in the main, of spring wire stock, it is within the purview of the invention to 55 provide a rigid framework if desired. In its broadest aspects, the invention contemplates the provision of a base structure and a superstructure, the former being either divided as illustrated herein, or simply slotted to provide an anvil having parallel side portions, or simply 60 having an opening therethrough and into which the fabric material may be forced by the eccentric camming action of a bell crank which operates upon the principles set forth herein. Therefore, only insofar as the invention has particularly been pointed out in the accompanying claims 65 is the same to be limited.

Having thus described our invention, what we claim and desire to secure by Letters Patent is:

1. An articulated two-piece clasp for securing the edge regions of overlapping fabric layers together, said clasp comprising: a framework and a bell crank pivoted thereto for swinging movement thereon, said framework being generally U-shape in vertical longitudinal cross section and providing a generally horizontal base support and an overlying superstructure connected thereto by a reverse 75 bend at the rear of the framework, the base support and

superstructure defining therebetween a forwardly opening mouth designed for edgewise reception of said overlapping fabric layers, said base support being provided with an elongated longitudinally extending slot therein, means at the distal end of the superstructure providing a pivotal support for the bellcrank whereby the latter is constrained to swing about a horizontal fulcrum axis extending transversely of the slot, said bellcrank including a fabric-engaging arm and a manipulative lever arm and being movable in a locking direction from a raised retracted position wherein said mouth is unobstructed to a lowered fabric-clamping position wherein the fabric-engaging arm projects across said mouth and into said slot to a leading over-center position with respect to the general plane of the base support, thus displacing a portion of the overlapping fabric layers within the mouth downwardly and forcing the same into the slot and laterally outwardly against the sides thereof under compression and in binding relationship, said manipulative lever arm being engageable with a portion of the superstructure for limiting the extent of swinging movement of the bellcrank in said locking direction after the fabric-engaging arm has moved to said over-center position whereby the compression of said fabric layers yieldingly urge said bellcrank to its locking position.

2. A clasp as set forth in claim 1, wherein the fabric-engaging arm is of a bulbous nature and presents a smooth uninterrupted side-surface contour which is directly engageable with the adjacent fabric layer within said mouth and which has a relatively low coefficient of friction with respect to the fabric material so as to be freely slidably thereon, the sides of said slot having a relatively high coefficient of friction with respect to the fabric material so as to restrain sliding of such material thereon during the impelling influence of said lever arm during swinging movement of the latter in its locking direction.

3. An articulated two-piece clasp for securing the edge regions of overlapping fabric layers together, said clasp comprising: a spring wire framework and a bell crank pivoted thereto, said framework being comprised of a length of spring wire stock bent to provide a U-shaped base structure presenting a pair of substantially parallel horizontal arms and an overlying superstructure likewise presenting a pair of substantially parallel arms which are connected at their rear ends to the rear end of the arms of the base structure by vertically extending reentrant bends, horizontal bight portions extending between the forward ends of each pair of parallel arms, said pairs of arms defining therebetween a forwardly opening mouth designed for edgewise reception of said overlapping fabric layers to such an extent that the extreme edges of the layers engage said reentrant bends, said bellcrank including a fabric-engaging arm and a manipulative lever arm and being fulcrumed on the bight portion of the superstructure for rotation in opposite directions about the axis of said bight portion, said bellcrank being movable in a locking direction from a raised retracted posi-

tion wherein said forwardly opening mouth is unobstructed for reception of the fabric layers to a lowered fabric-clamping position wherein the fabric-engaging arm projects across said mouth and enters between the parallel arms of the base structure and moves to a leading over-center position with respect to the plane of said horizontal arms, thus displacing a portion of the overlapping fabric layers within the mouth downwardly and forcing the same between and generally laterally outwardly against such arms in binding relationship, the effective width of said manipulative lever arm being greater than the distance between the arms of said superstructure and the effective angularity of the bellcrank being such that the opposite side portions of the lever arm will come to rest upon the arms of the superstructure and establish the over-center position of the fabric-engaging arm, the bight portion associated with the base structure being disposed an appreciable distance forwardly of the horizontal bight portion associated with the superstructure and also forwardly of the fabric-engaging arm when the latter is in its fabric-clamping position, thus maintaining the bight portion of the base structure out of clamping engagement with the fabric layers.

4. A clasp as set forth in claim 3, wherein the fabric-engaging lever arm is of a bulbous nature and presents smooth uninterrupted side surfaces which are directly and slidably engageable with the adjacent fabric layer within said mouth, the frictional characteristics of the parallel arms of the base structure being such as to restrain sliding of the adjacent fabric layer thereon during movement of the bellcrank to and from its lowered position.

5. A clasp as set forth in claim 4, wherein the manipulative lever is formed with a pair of grooves therein within which the parallel arms of the superstructure are received when said manipulative lever comes to rest thereon and by means of which grooves said latter arms are constrained against outward spreading movement under the influence of the wedging action exerted by the fabric layers when the bellcrank is in its lowered position.

6. A clamp as set forth in claim 5, wherein the forward end regions of the parallel arms of the base structure are inclined upwardly whereby the interconnecting bight portion therebetween is disposed above the level of said latter arms.
